UNITED STATES PATENT OFFICE.

ERMIN F. PLUMB, OF STREATOR, ILLINOIS, ASSIGNOR TO STREATOR BRICK COMPANY,
OF STREATOR, ILLINOIS, A CORPORATION OF ILLINOIS.

BRICK-MACHINE.

1,202,581.

Specification of Letters Patent. Patented Oct. 24, 1916.

Application filed June 3, 1916. Serial No. 101,534.

To all whom it may concern:

Be it known that I, ERMIN F. PLUMB, a citizen of the United States, residing at Streator, in the county of La Salle and 5 State of Illinois, have invented certain new and useful Improvements in Brick-Machines, of which the following is a specification.

This invention relates to brick making 10 machinery and more particularly to that class of such machines adapted to produce ornamental brick of rough exterior, and has for its primary object the construction of a machine of the character set forth which 15 shall be adapted to produce fine quality ornamental brick of distinctive design with a minimum of operating expenditure.

A further object of this invention is to 20 construct a machine of the class described which shall be adapted to operate intermediate the column forming mechanism and the cutting off device, in order that the 25 ornamenting step may take place between the column forming and cutting off operations.

A further object of this invention is to 30 provide means for regulating the depth of cut of the ornamenting mechanism acting upon the clay stream whereby to control the depth of the design imparted thereto.

With the foregoing and other objects in view, as will from time to time appear, this invention consists in the peculiar arrangement and combination of the various 35 co-operating elements of a brick making machine as hereinafter described in the following specification and more particularly set forth in the appended claims.

Referring to the accompanying drawings 40 illustrating the preferred embodiment of the invention and in which the same reference characters indicate the same parts wherever used, Figure 1 is a perspective view of the front end of the machine; Fig. 2 is a perspective view of the rear of the machine; Fig. 3 is a top view of the machine. Fig. 4 is an end elevation showing the clay stream in section and, Fig. 5 is a side elevation on a somewhat larger scale with a 45 portion of the machine broken away, in order to give clearness of illustration.

4 designates the mouth of any suitable clay column forming machine used in brick making machine plants and constituting no portion of my invention. This 50

clay forming machine delivers a solid column of clay adapted to be cut into brick form by suitable mechanism.

Carried upon a roller 5 and other suitable supporting means at the other end of the machine (not shown) is an endless belt or apron 6 adapted to receive the clay column 7, as it issues from the mouth of the machine 4. The roller 5 is supported by an axle 8, which is in turn driven by any suitable external source of power. Extending longitudinally of the clay stream are side plates 9, 9 which support uprights 10, 11 and 12, the uprights 10 and 11 being connected at their upper ends by a cross member 13, and the uprights 11—12 braced by a cross member 13'.

Upon the members 11 and 12 are bearings 14 and 15 supporting a shaft 16 which carries a friction wheel 17 provided with a pulley 18 adapted to be driven by a belt 19 from any suitable external source of power. The uprights 10 and 11 carry a second set of bearings 20, 20, which support a transverse shaft 21 carrying a friction disk 22 adapted to engage the friction disk 17 at right angles to the face thereof and being adjustable across the face of the member 17 by means of a slotted member 23 having a handle 24 by means of which the disk 22 may be slid longitudinally of the shaft 21, it being slip-keyed thereon for the purpose, the position of said wheel 22 being governed by means of wing nuts 25 and 26 adapted to operate in the slot 27 of the member 23.

Upon the shaft 21 suitably spaced apart are mounted eccentrics 28, 29, carrying eccentric straps 30, 31, respectively, the eccentric straps being provided with extensions 32, 33, which extensions support depending rods 34, 35, being provided respectively with springs 36, 37, and being adjustably bolted at their lower ends by means of nuts 36' and 37' to a cross bar 38 which transversely connects longitudinally extending spring members 39 and 40 which extend rearwardly of the machine to a point 41 where they are bent upwardly and fastened at 42 to a frame-work comprising uprights 43 and 44, a connecting cross bar 45, similar uprights 46, 47 and a similarly connecting cross bar 48, the spring members 39 and 40 extending to cross member 48 where they are suitably fastened. Mounted between the members 39 and 40

and extending across the face of the clay stream is a plate 49 adjustably supported upon the members 39, 40 by means of bolts 40' engaging a cross bar 50 and provided with a plurality of adjustable spikes 51 extending through the adjustable plate 49 to a point slightly above the face of the clay column.

Upon the upright 10 is a stub shaft 52 and upon the uprights 11 and 12 is a similar shaft 53, each of said shafts 52 and 53 carrying an angle shaped member 54 held in place thereon by means of U bolt 55, the inner ends of each of the members 54 being connected to the corresponding member 39 or 40 by means of an adjustable connecting rod 56 provided with a spring 57 and a regulating nut 57'. The lower end of each of the members 54 carries a connecting rod 58 cushioned by means of a spring 59, and provided with a hand wheel 59' adapted to regulate the distance of members 54 from the side bars and also the tension of the springs 57, the connecting rods being fastened to spring members 60 which extend lengthwise of the side face of the clay column rearwardly to the frame-work above described, where the members 60 pass through stirrups 61 upon the supports 43, 44, as the case may be, and terminate adjacent the support 46, 47 to which they are bolted by means of an extension 62. Each of the members 60 carries by means of a bracket 63 an adjustable plate 64 mounted thereon by means of bolts 63', and similar in construction to the plate 49 and provided with a plurality of adjustably held spike members 65 which extend to a point immediately adjacent the side faces of the column 40 on either side thereof.

Mounted upon the uprights 43 and 46 by means of suitable bearings 66 and 67 is a shaft 68 which carries a pulley 69 and a cylindrical brush 70. Upon the shaft 21 are a plurality of pulleys 71 adapted for different speeds from which extends a belt 72 around a belt tightener 73 of any suitable type mounted upon a bracket 74 extending from the support 44 and to the pulley 69 adapted to impart the rotation of the shaft 21 to the shaft 68 to cause a rotation of the brush held thereon.

The brush 70 mounted in the bearings 66 and 67 is adapted to be adjusted toward or away from the face of the clay stream by means of a threaded member 75 mounted upon a bracket 76 and adapted to raise or lower the end bearing 67 in order to increase or decrease the pressure at which the brush 70 engages the face of the clay column 7, the brush being normally held in close contact with the face of the clay stream by means of a nut 77.

The bearing 66 is held in place by a pin 78 mounted upon a U-shaped member 79

having a screw-threaded shaft 80 extending therefrom and adapted to engage a block 81 suitably held upon one of the uprights and to be held in place in the block by means of a nut 82, so that when it is desired to adjust the height of the bearing 66 with relation to the clay stream the pin 78 may be removed and the nut 82 loosened, whereupon the shaft 79 may be adjusted in the block 81 to the desired degree and the pin 78 replaced 75 in position, and the nut 82 tightened, in order to hold the same in the proper position.

Due to the adjustability of the plates carrying the spikes adapted to act upon the sides and face of the clay stream, and the further adjustability of the throw of the levers and connecting rods adapted to cause the reciprocatory movement of said plates, a varied degree of depth of cut of the spikes 85 carried by the said plates may be obtained, thus providing at the will of the operator a variation in the design imparted to the clay column. In order to compensate for this adjustability the brush 70 must of 90 necessity be adjustable likewise, which is made possible by means of the mechanism just described.

The operation of the machine as above described is as follows: The clay column 93 formed by the clay forming machine passes outwardly through the mouth onto the belt conveyor 6, and travels at a uniform speed through the mechanism above described. As the clay stream passes under the spikes 51 carried by the plate 49 mounted upon the spring members 39 and 40, a vertical adjustable reciprocatory movement is imparted to the plate 49 and its corresponding supporting members by means of the rods 34 105 and 35 which are vertically reciprocated by the eccentrics 28 and 29 rotating with the shaft 21, which is driven by means of the friction disk 22 engaging the second friction disk 17, which is in turn driven from any 110 suitable source of power indicated by the belt 19, the speed of the vibratory movement being regulated as described by means of shifting the disk 22 across the face of the disk 17 in the well known manner. The 115 vertical vibratory movement of the members 39 and 40 is communicated to the members 54 by means of the adjustable connecting rods 56 and from the members 54 by means of the connecting rod 58 to the side 120 spring members 60 carrying the plates 64 which are in turn vibrated in unison with the plate 49 through the medium of the mechanism just described. The result of this vibratory movement of the plates 64 125 and the plate 49 is to cause the spikes 65 and 51 carried thereby to "peck" the top and side faces of the column to produce a roughened surface which, in the completed brick, gives a very desirable rough texture 130

finish. The clay particles which are cut out from the clay column by the spikes of the various plates are brushed off the face of the clay column by means of the brush 70 which is rotated by the belt 72, the brush also serving to take off the sharp corners of the indentations left by the spikes and thus has some further effect in ornamenting the brick. The particles cut off by the side 10 plates fall from the clay column by gravity, thus leaving the side faces free.

As many changes could be made in the above construction, and many apparently widely different embodiments of my invention could be made, without departing from the scope thereof, it is intended that all matter contained in the above description or shown in the accompanying drawings shall 15 be interpreted as illustrative and not in a limiting sense.

Having thus described my invention what I claim as new and desire to secure by Letters Patent is:

1. In a machine for marking a clay column, means for conveying the clay column, a plurality of markers, and means for reciprocating said markers in unison and in a direction at a right angle to the path of movement of said clay column to alternately 25 engage and disengage a face thereof.

2. In a machine for marking a clay column, means for conveying the column, a plurality of members adapted to operate upon the faces of the column to cut out 35 small clay particles therefrom, and means for reciprocating said members in unison and in a direction at a right angle to the path of movement of said clay column to alternately engage and disengage a face 40 thereof.

3. In a machine for marking a clay column, means for conveying the column, a plurality of markers comprising cutting units adapted to cut out small clay particles 45 from the column, and means for reciprocating said cutting units in unison and in a direction at a right angle to the path of movement of said clay column to alternately engage and disengage a face thereof.

4. In a machine for marking a clay column, the combination with means for conveying the column, of a frame-work above said column, a shaft on said frame-work, means for driving said shaft, eccentrics on 55 said shaft, connecting rods from said eccentrics, and a plurality of marking devices adapted to be operated by said connecting rods to alternately engage and disengage the desired faces of the clay column.

5. In a machine for marking a clay column, means for conveying the clay column, a plurality of reciprocating markers adapted to engage the desired faces of said column, and means for brushing the particles thus 65 cut out from the face of the clay column.

6. In a machine for marking a clay column, the combination with means for conveying the column, of a plurality of vibrating members adapted to operate upon the face of the clay column to cut out small 70 clay particles therefrom, and means for brushing the particles thus cut out from the face of the clay column.

7. In a machine for marking a clay column, the combination with means for conveying the column, of a plurality of interconnected resiliently mounted marking devices, and means adapted to cause said marking devices to simultaneously vibrate against the desired faces of the clay column and in 75 a direction at a right angle to the path of movement of said clay column.

8. In a machine for marking a clay column, the combination with means for conveying the column, of a plurality of resiliently mounted marking devices, means adapted to cause said marking devices to vibrate against the desired faces of the clay column and in a direction at a right angle to the path of movement of said clay column, 80 and means for removing the clay particles cut out by the marking devices.

9. In a machine for ornamenting a clay column, the combination with means for conveying the clay column, of a marking device mounted to act upon the top face of the clay column, marking devices adapted to act upon the side faces of the clay column, and means connecting the side marking device and the top face marking device to 95 cause them to engage and disengage the faces of the column simultaneously.

10. In a machine for ornamenting a clay column, the combination with means for conveying the clay column, of a marking device mounted to act upon the top face of the clay column, marking devices adapted to act upon the side faces of the clay column, means connecting the side marking device and the top face marking device to 100 cause them to operate simultaneously, and means adapted to clear the surface of the clay column of the particles of clay cut out by the marking devices.

11. In a machine for ornamenting a clay column, the combination with means for conveying the clay column, of a marking device mounted to act upon the top face of the clay column, marking devices adapted to act upon the side faces of the clay column, 110 means connecting the side marking device and the top face marking device to cause them to operate simultaneously, means adapted to clear the surface of the clay column of the particles of clay cut out by 115 the marking devices, and means for adjusting the pressure of said column clearing means upon the column.

12. In a machine for ornamenting a clay column, the combination with means for 120

- conveying the column, of a resiliently mounted marking plate adjacent the top face of the column, a resiliently mounted marking plate adjacent each side face of the column, means for causing a vibration of the top face marking device against the column, and means connecting the top face marking device and the side face marking devices to cause all of the marking devices to operate against the clay column in unison. 5
13. In a machine for marking a clay column, the combination with means for conveying the clay column, of a plurality of resiliently mounted marking devices, means for causing said marking devices to vibrate against the clay column to cut the same, means for regulating the speed of such vibration, and means for resmoothing the clay column after the marking operation by said 15 marking devices. 14. In a machine for marking a clay column, means for conveying the clay column, a plurality of reciprocating markers adapted to alternately engage and disengage the desired faces of said column, said markers moving in a path at a right angle to the path of movement of said column, and means for adjusting the distance between said markers and said clay column. 20
15. In a machine for marking a clay column, the combination with means for conveying the column, of a plurality of markers adapted to cut out small clay particles therefrom, means for reciprocating said marking devices to engage and disengage said clay column, said markers moving in a path at a right angle to the path of movement of said column, and means for adjusting the depth of cut of said marking 25 devices. 16. In a machine for marking a clay column, the combination with means for conveying a clay column, of a plurality of vibrating members adapted to operate upon the clay column to cut out small clay particles therefrom, means for brushing the particles thus cut from the face of the clay column, and means for adjusting the distance of said brushing means toward and away 30 from said column. 17. In a machine for ornamenting a clay column, the combination with means for conveying the clay column, of a marking device mounted to act upon the top face of the clay column, means for reciprocating 35
- said device, means for adjusting the depth of cut, marking devices adapted to act upon the side faces of the clay column, means connecting the side marking devices and the top face marking device to cause them to operate simultaneously, means for adjusting said connecting means, means adapted to clear the surface of the clay column of the particles of clay cut out by the marking devices, means for adjusting the distance of said marking devices toward and away from said clay column, and means for adjusting the distance of said clearing device toward and away from said clay column. 40
18. In a machine for marking a clay column, the combination with means for conveying the column, of means adapted to reciprocate toward and away from the faces of said column to mark the same, means adapted to reciprocate toward and away from the sides of said column to mark the same, all of said marking means moving in a direction at a right angle to the path of movement of said clay column, and means for independently adjusting the depth of cut of each of said marking devices. 45
19. In a machine for marking a clay column, the combination with means for conveying the column, of means adapted to reciprocate toward and away from the faces of said column to mark the same, means adapted to reciprocate toward and away from the sides of said column to mark the same, means for independently adjusting the depth of cut of each of said marking devices, and means for brushing off the particles cut out by said marking devices. 50
20. In a machine for marking a clay column, means for conveying the column, a plurality of markers comprising cutting units adapted to engage and disengage the clay stream with a picking action to cut out small clay particles from the column, and means for reciprocating the cutting units in unison and in a direction at a right angle to the path of movement of said clay column, to alternately engage and disengage the faces of said column. 55

In testimony whereof I affix my signature in the presence of two witnesses.
